CLAIM

(57) The ornamental design for a light engine, as shown and described.

DESCRIPTION

FIG. 1 is a front perspective view of the light engine.

FIG. 2 is a front elevation view of the light engine.

FIG. 3 is a rear elevation view of the light engine.

FIG. 4 is a right elevation view of the light engine (the left side is a mirror image of this side).

FIG. 5 is a top view of the light engine; and,

FIG. 6 is a bottom view of the light engine.

The broken lines in the drawings depict portions that are not part of the claimed design, but rather show the environment in which the design is associated.
